UNITED STATES PATENT OFFICE.

GEORGE A. LINCOLN, OF EAST SOMERVILLE, MASSACHUSETTS.

IMPROVEMENT IN SASH OPENING AND CLOSING MECHANISMS.

Specification forming part of Letters Patent No. 158,850, dated January 19, 1875; application filed December 19, 1874.

To all whom it may concern:

Be it known that I, GEORGE A. LINCOLN, of East Somerville, of the county of Middlesex and State of Massachusetts, have invented a new and useful Improvement in Mechanism for Opening and Closing Window-Sashes; and do hereby declare the same to be fully described in the following specification, and represented in the accompanying drawings, of which—

Figure 1 is a front elevation, and Fig. 2 a side elevation, of a door-frame and ventilating-sash with my invention applied thereto. Fig. 3 is a vertical section of such taken through the spring-bolt.

My invention mainly consists in the combination of an arm and series of guide-wheels to be projected from a door-frame, with a bolt and its case provided with another arm and guide-wheel, and to be applied to a sash, all being to operate with two cords, as and for the purposes as hereinafter set forth.

In such drawings, A denotes the door-frame and B the sash, which at bottom is connected with the frame A by hinges *a a*, in order for the sash to be turned from a vertical down into an inclined position, chains *b b* being fixed to the sash and frame, in order to determine the extent of depression of the sash. A spring-bolt, C, attached to the upper rail of the sash, has a catch, D, over it and applied to the door-frame. The said catch forms part of a bracket or arm, E, that extends from the door-frame in manner as shown, and supports a series of grooved wheels, *c, d, e, f*, and *g*, arranged in it as represented. Furthermore, there is extended from the bolt-case F an arm, G, also two ears, *h h*, the latter serving to support the axle of another grooved wheel, *i*, arranged between them. From a knob, *k*, extending from the spring-bolt a cord, *l*, projects down to and partly around the wheel *i*; thence to and partly

around the wheel *d*, thence to and partly around the wheel *e*, thence to and partly around one of a pair of grooved wheels, *m n*, arranged as shown, and having their frame *o* fixed to the upper part of the door-frame. Another cord, *p*, fastened to the arm G, extends to and partly around the wheel *g*, thence to and partly around the wheel *e*, thence to and partly around the wheel *f*, and thence to and partly around the other of the pair *m n* of wheels, both cords being led down to and wound around a belaying cleat or hook, *r*, projecting from the door-frame.

By pulling down the first cord *l*, we shall not only move the bolt downward out of engagement with its catch, but open the sash or draw it outward.

The other cord, *p*, is to effect the raising and closing of the sash, which cannot be accomplished by the cord *l*.

With my mechanism applied to a door and its sash, the latter may be unlocked and opened to any desirable extent for ventilation, and afterward be readily closed and locked.

I claim—

1. The combination of the arm E, its guide-wheels *c, d, e, f*, and *g*, and bolt-catch with the bolt C, and its case F, provided with the arm G and guide-wheel *i*, all being substantially as described, and to operate with cords, as and for the purpose set forth.

2. The combination and arrangement of the pair of guide-wheels *m n*, applied to the door-frame, with the arm E and its guide-wheels, and with the bolt and case provided with the wheel and arm, and applied to the sash, all being arranged as specified.

GEO. A. LINCOLN.
